Attorney.

UNITED STATES PATENT OFFICE.

CHARLES J. TRAVERS, OF PORT WASHINGTON, WISCONSIN.

ADJUSTMENT FOR THE BACKS OF TYPE-WRITER CHAIRS.

1,263,159.

Specification of Letters Patent. Patented Apr. 16, 1918.

Application filed September 4, 1917. Serial No. 189,517.

To all whom it may concern:

Be it known that I, CHARLES J. TRAVERS, a citizen of the United States, residing at Port Washington, in the county of Ozaukee, 5 State of Wisconsin, have invented a new and useful Adjustment for the Backs of Type-Writer Chairs, of which the following is a specification.

This invention relates to improvements in 10 that class of chairs for type-writer operators and others, wherein an adjustable spring-supported back-standard is employed; and the principal objects of the invention are to increase the rigidity, durability, and lightness of the adjustment, and at the same time, 15 reduce the cost of manufacture and provide conveniently accessible means for regulating the spring-tension and the inclination and elevation of the back-standard as well as the 20 back-pad carried thereby.

Other objects of the invention will hereinafter appear, and the novel features thereof will be more particularly pointed out in the appended claims.

25 Referring to the drawing:

Figure 1 is a top plan view of an adjustment for type-writer chairs embodying my invention, the front portions of the spider-arms being broken away to conserve space, 30 and the back standard supporting-arm and the back-standard being shown partly and wholly in section, respectively.

Fig. 2 is a side elevation of the same, the back-standard being broken away at its 35 upper portion and its lower end shown in vertical section;

Fig. 3 is a detail in perspective of the hollow or tubular bridge-piece;

Fig. 4 is a similar view in detail of the 40 back-standard supporting-yoke; and

Fig. 5 is a detail in plan of the spring-supporting clip.

Similar numerals of reference indicate 45 similar parts in all the figures of the drawing.

In practising my invention I employ opposite companion spider-arms 1, such being preferably formed of sheet-metal angle-iron, and arranged so that their upper horizontal flanges are outwardly disposed. These arms 50 1 may be connected at their rear ends by a transverse brace 2, the ends of which overlap the spider-arms and are riveted thereto,

as at 3. The ends of the spider-arms are provided with apertures 4, for the reception 55 of screws by means of which the seat (not shown) may be secured in position.

At about their middles, the spider-arms may and preferably are connected by a hollow or tubular bridge 5, and the same is 60 preferably formed of two interlocking sections, designated, respectively, as the upper section 6 and the lower section 7. The section 6 is preferably of inverted U-shape in cross-section and formed with the opposite 65 depending sides 8, the latter having formed in their lower edges and about midway their lengths, shallow mortises 9. The section 7 is preferably a flat plate, corresponding in length with the section 6 and of a width 70 adapting it to fit between the depending sides 8, and at opposite sides is provided with tenons 10, corresponding to and adapted to enter and snugly fit within the mortises 9. By means of the mortises and tenons 9 75 and 10, and the embracing depending sides of the upper section, it will be seen that the two sections are securely and immovably interlocked together, the two sections being 80 tube-like in form and appearance and capable of successfully resisting the lateral strains to which they are necessarily subjected in the ordinary use of the chair. The opposite ends of the tubular bridge are formed with tenons 11, located at intervals, 85 and these enter corresponding mortises 12, formed in the vertical flanges of the spider-arms 1, beyond which the said tenons are upset or headed. In this manner, it will be 90 observed, these three parts—the two spider-arms and the bridge—are as rigid as if formed in one piece, all rivets being avoided.

The upper and lower sections 6 and 7 forming the bridge are provided with vertically alining apertures 13, and these receive 95 the upper reduced end of the usual supporting-standard 14. By reducing this standard at its upper end, which is the usual practice, a shoulder is formed at the lower end of the reduction, and upon this shoulder is seated 100 the lower section 7 of the bridge. If desired, a short spacing-sleeve 6^a, (see dotted lines Fig. 2) may encircle the reduced upper end of the supporting-standard 14, the same being located between the upper and lower sections 6 and 7 of the bridge. If employed, 105

this sleeve may be inserted within the bridge during the process of assembling the two sections composing the latter. Above the bridge, the supporting-standard 14 is headed in the usual manner, so that the connection formed is permanent.

Having its opposite ends located in suitable apertures formed in the vertical flanges of the spider-arms, immediately in rear of the bridge 5, is a transverse pintle 15, the ends of the latter being upset or headed. Upon this pintle are hung the front apertured ends of a pair of back-standard supporting-arms 16, the latter being formed of sheet-metal stock preferably of uniform width. The arms 16 are positioned between the two spider-arms and extend rearwardly beyond the same a suitable distance and converge as shown.

20 The brace 2 is formed with a central aperture through and from which depends a tension-bolt 17, the same carrying an apertured spring-supporting washer 18, and below, a hand-wheel 19. As best shown in Fig. 5, the washer is provided with a central bolt-receiving aperture 19^a, opposite parallel grooves 20, and beyond the same has its edge at diametrically opposite points upturned to form flanges 21.

30 A cross-brace 26, formed of sheet-metal, and formed with down-turned ends, is interposed between the arms 16, and serves to connect the same, the brace being located immediately in advance of the brace 2 or 35 at any other convenient point tending to lend stability and rigidity. The ends of the brace 26 are, in this instance, riveted, as at 27, to the arms 16, but any other connection may be employed.

40 Coiled about the pintle 15, as at 23, at opposite sides of the center of said pintle, are two springs 22. Each of these springs is formed with upper and lower rearwardly disposed terminals, respectively designated as 24 and 25. The upper terminals 24 of these springs engage under the transverse brace 26 connecting the two arms 16, while the lower terminals 25 of the springs are engaged or rest upon the washer 18, being received by the grooves 20 thereof and retained in position by the flanges 21. It will be obvious that the tendency of the springs being to spread their terminals, the upper terminals will exert a lifting tendency to the arms 16 and therefore yieldingly resist a downward tendency of said arms, this resistance being increased or diminished, or in other words, regulated by a manipulation of the hand-wheel 19 upon the tension-bolt 17.

Between the rear ends of the arms 16 is located, in this instance, an angular or U-shaped sheet-metal yoke 28, the forwardly projecting sides of which are pivotally connected near their rear ends to the corre-

sponding ends of the arms 16, by means of rivets 30. Near their front or opposite ends, the arms or sides 31, of the yoke are provided with opposite companion segmental slots 32, concentric with the opposite rivets 70 30, passing through apertures 29, formed in the yoke, and through the latter slots and through corresponding apertures 33, the latter formed in the arms 16, is passed a clamping-bolt 34, at one end of which is 75 threaded a clamping hand-wheel 35. The yoke is capable of being tilted or adjusted on its pivots (the rivets 30) and secured in any of its adjusted positions by means of the hand-wheel, the latter causing the arms 16 80 to frictionally engage with the sides of the yoke 28. I may, in addition, encircle the clamping-bolt 34 by a spacing-sleeve 36, the same being interposed between the sides 31 of the yoke. If used, it will be seen that 85 the sides of the yoke will be clamped between the ends of the sleeve and the arms 16. This sleeve may be omitted if desired.

Within the yoke 28 is mounted the lower end of the back-standard 37, and the two 90 may be rigidly connected in any suitable manner, or as herein illustrated, the standard may be mounted in the yoke in such manner as to render the standard vertically adjustable. If adjustably mounted in the 95 yoke, the back-pad (not shown) which is usually mounted adjustably at the upper end of the standard, may be secured rigidly to the standard, so that not only is the cost of this usually-employed adjustable fitting 100 saved in the manufacture of the chair, but the usual and undesirable projections incident to such fittings are omitted, the latter being unsightly and also affording a means for catching and tearing the apparel of the 105 chair-user. In the present instance by providing the lower end of the back-standard with a longitudinal slot 38, for the reception of a clamping-bolt 40, and the rear wall of the yoke 28 with an aperture for said bolt, it will be apparent the said standard 110 is capable of vertical adjustment with relation to the chair-seat, an ordinary clamping hand-wheel threaded on the rear end of the bolt, as at 41, serving to secure the standard 115 at the proper elevation. The back-pad being rigid with the standard will, of course, thus be elevated or lowered, as the case may be, the limit of adjustability being in accord with the length of the slot in the standard. 120 Any other simple means may be substituted for those shown, or this adjustable feature, just described, may be omitted and the back-pad and standard adjustably connected in any of the well-known ways.

125 It will be appreciated that the entire adjustment, with the exception of the springs, rivets, and kindred parts, is constructed from ordinary sheet-metal stock and with very great economy, and that the various 130

adjustments may be regulated by simple means readily accessible to the occupant of the chair.

Having described my invention, what I claim is:

1. In a chair-adjustment, the combination with opposite spider arms formed of sheet-metal and angular in cross-section, of a connecting tubular bridge, the ends of the bridge being provided with tenons and the vertical webs of the spider-arms having corresponding mortises receiving the tenons, and the latter being upset at their ends. 10
2. In a chair-adjustment, the combination with opposite spider-arms formed of sheet-metal and having mortises, of a connecting bridge, angular in cross-section and formed of sheet-metal and having tenons at its ends engaging said mortises. 15
3. In a chair-adjustment, the combination with opposite spider-arms formed of sheet-metal and having mortises, of a connecting bridge, tubular in cross-section, and consisting of an upper inverted U-shaped section and a lower flat section engaging the depending sides of the upper section, said bridge having tenons at its ends engaging the mortises of the spider-arms. 20
4. In a chair-adjustment, the combination with opposite sheet-metal spider-arms provided with mortises, of a connecting bridge, tubular in cross-section, and comprising an upper inverted U-shaped section, the lower edges of the sides of which are provided with shallow mortises, and a lower flat section received by the opposite depending sides of the upper section and provided at its opposite edges with tenons interlocking with said mortises of the upper section, the 25
5. In a chair-adjustment, the combination with opposite spider-arms formed of sheet-metal and having mortises formed in their vertical webs, of a tubular bridge comprising upper and lower interlocking sections each provided with a central aperture and with end-tenons received by the mortises of the spider-arms, beyond which said end-tenons are upset and an adjusting-standard 30 reduced below its upper end to form a shoulder and having its upper reduced end passed through the central aperture of the bridge, above which latter the adjusting-standard is headed, the shoulder of said standard engaging under the bottom of said bridge. 35
6. In a chair-adjustment, the combination with opposite spider-arms formed of sheet-metal and provided with mortises, of a tubular bridge having tenons at its ends entering said mortises, said bridge being composed of upper and lower sections interlocked to resist independent movement 40 and provided with alining apertures, an adjusting standard reduced at its upper end and passing through said apertures and having its shoulder, formed by said reduction, resting against the underside of the lower section, and a spacing-sleeve encircling the reduced portion of the standard 45 and interposed between the upper and lower sections of the bridge. 50

CHARLES J. TRAVERS.
